JOHN F. HALE, OF CHICAGO, ILLINOIS, ASSIGNOR TO WARREN WEBSTER AND COMPANY, A CORPORATION OF NEW JERSEY.

STEAM-TRAP.

SPECIFICATION forming part of Letters Patent No. 752,067, dated February 16, 1904.

Application filed June 18, 1903. Serial No. 162,005. (No model.)

To all whom it may concern:

Be it known that I, JOHN F. HALE, of the city of Chicago, county of Cook, State of Illinois, have invented an Improvement in Steam-5 Traps, of which the following is a specification.

My invention relates particularly to steam-traps in which the outflow of water of condensation is controlled by a float-valve and the 10 air is allowed to escape through a normally open by-pass which may, if desired, be controlled by a thermostatic valve. In such traps difficulty has been experienced owing to the 15 liability of the water of condensation when there is a large flow closing up the air passage-way before the float operates to open the discharge-outlet.

It is one of the objects of my invention to overcome this difficulty, and this I accomplish 20 by providing the body of the trap with an internal partition adjacent to the inlet end, forming a chamber communicating with the inlet and having at its upper portion an air-vent into the upper portion of the interior of the 25 trap-body and at its lower portion a water-opening into the lower portion thereof. By this means separate inlets for the water and air are afforded into the body of the trap, and the air has at all times a clear unobstructed 30 passage-way to the outlet.

Another object of my invention is to separate and discharge the sediment from the water passing into the body of the trap. This is effected by arranging a screen in the water-opening in the lower portion of the chamber 35 and providing it with a discharge-outlet fitted with a removable cap. As all the water must pass through this chamber before entering the body of the trap, the sediment will be retained 40 therein and can readily be discharged through the discharge-outlet when the cap is removed.

In the drawings, Figure 1 is a longitudinal vertical sectional view of a steam-trap embodying my invention, and Fig. 2 is a transverse vertical sectional view of the same on the line A A of Fig. 1.

a is the body of the trap, having the inlet a' and outlet a'' .

a^3 is the cap or cover.

b is the float-controlled valve-piece, which 50 controls the outlet a'' . As shown, it is a tubular piece guided in a hollow cage c ; which is screwed into the outlet a'' and carries the valve-seat c' . The valve-piece b is operated by a float-lever d , extending through a transverse 55 hollow guide E in the valve-piece and fulcrumed, as at d , to an extension on the cage. The free end of the lever d carries the float f , and as the float rises and falls under the action of the water the lever d , bearing on the 60 walls of the guide E , opens or closes the valve-piece b .

The upper end of the cage c carries a thermostatic valve device. As shown, this consists of a cylindrical shell g , carried by a thimble h , screwed into the upper open end of the cage, the perforated plugs i in the top and bottom of the shell and the composition expanding-piece j between the plugs adapted when expanded to close the aperture k in the 70 upper plug. The thermostatic valve device projects through an opening a^4 in the cap or cover a^3 and is inclosed by a bonnet l . When the thermostatic expanding-piece j is contracted and the valve-piece b is closed, the 75 air may pass freely through the opening k in the plug i , thence down the tubular shell g through the openings m in the lower plug i' , and out through the tubular valve-piece b to the outlet a'' . When, however, steam reaches 80 the piece j and expands it, the passage-way k is closed.

So far as the trap has been described it is of known construction and has been described simply for the purpose of rendering my improvements more intelligible. With such traps as heretofore constructed difficulty has been experienced in collecting the dirt and sediment carried into the trap with the water of condensation and enabling it to be removed. 85 For this purpose I provide the inlet end of the trap with an internal inlet chamber or passage-way n , into which the inlet a' opens at the upper end and from which the water passes into the body of the trap through a screened 90 opening from the lower portion. The screen a , which is shown as a perforated plate, may be held in its seat about the opening n' by a

spring ν and screw-cap τ in the lower part of the chamber n . All the water entering the trap must pass through this chamber or passage-way n , and the solid matter will be arrested by the screen and collected in the bottom of the chamber n , from which it may be discharged on the removal of the cap τ . Another difficulty which has heretofore existed in traps of this character has been in preventing the accumulation of water of condensation from forming a water seal for the air. This is obviated by the formation of an air-opening s in the upper part of the chamber n above the inlet a' . The body of the trap is preferably enlarged or made deeper at its inlet end, so as to form a well for the float. This will enable the float to operate and discharge the water before the air passage-way can become closed and will insure the air passage-way being always kept open except when the thermostatic plug j is closed on its seat by the action of the steam.

What I claim as new, and desire to secure by Letters Patent, is as follows:

- 25 1. In a steam-trap of the character described, the combination of the trap-body having an inlet and an outlet, a float-controlled valve for controlling said outlet, said trap being further provided with an air by-pass about said valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof.
- 30 2. In a steam-trap of the character described, the combination of the trap-body having an inlet and an outlet, a float-controlled valve for controlling said outlet, said trap being further provided with an air by-pass about said valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof.
- 35 3. In a steam-trap of the character described, the combination of the trap-body having an inlet and an outlet, a float-controlled valve for controlling said outlet, said trap being further provided with an air by-pass about said valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof, said chamber being further provided with an opening for the discharge of sediment, and a removable cap for said opening.
- 40 4. In a steam-trap of the character described, the combination of the trap-body having an inlet and an outlet, a float-controlled valve for controlling said outlet, said trap being further provided with an air by-pass about said valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof, the body of said partition between said air-vent and water-opening being closed.
- 45 5. In a steam-trap for the purpose described, the trap-body having an inlet and an outlet and provided adjacent to its inlet end with an internal partition forming a chamber communicating with the inlet and having at its upper portion an air-vent into the upper portion of the interior of the trap-body and at its lower portion a water-opening into the lower portion thereof, the body of said partition between said air-vent and water-opening being closed.
- 50 6. In a steam-trap for the purpose described, the trap-body having an inlet and an outlet and provided adjacent to its inlet end with an internal partition forming a chamber communicating with the inlet and having at its upper portion an air-vent into the upper portion of the interior of the trap-body and at its lower portion a water-opening into the lower portion thereof, the body of said partition between the air-vent and water-opening being closed and a discharge-opening for sediment adjacent to said water-opening, and a removable cap for said discharge-opening.

valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof, and a screen located in said water-opening.

4. In a steam-trap of the character described, the combination of the trap-body having an inlet and an outlet, a float-controlled valve for controlling said outlet, said trap being further provided with an air by-pass about said valve between the outlet and the upper portion of the interior of the trap-body, the trap-body being provided adjacent to the inlet end with an internal partition forming a chamber communicating with the inlet and having at its upper portion an air-vent into the upper portion of the interior of the trap-body and at its lower portion a water-opening into the lower portion thereof, said chamber being further provided with an opening for the discharge of sediment, a removable cap for said opening for the discharge of sediment, a removable screen in said water-opening, and a spring between said removable cap and screen for retaining the screw in place.

5. In a steam-trap for the purpose described, the trap-body having an inlet and an outlet and provided adjacent to its inlet end with an internal partition forming a chamber communicating with the inlet and having at its upper portion an air-vent into the upper portion of the interior of the trap-body and at its lower portion a water-opening into the lower portion thereof, the body of said partition between said air-vent and water-opening being closed.

6. In a steam-trap for the purpose described, the trap-body having an inlet and an outlet and provided adjacent to its inlet end with an internal partition forming a chamber communicating with the inlet and having at its upper portion an air-vent into the upper portion of the interior of the trap-body and at its lower portion a water-opening into the lower portion thereof, the body of said partition between the air-vent and water-opening being closed and a discharge-opening for sediment adjacent to said water-opening, and a removable cap for said discharge-opening.

In testimony of which invention I hereunto set my hand.

JOHN F. HALE.
